CONSTRUCTION FOR DOUBLE-WALLED
INSULATED CONTAINERS

Henry C. Kornemann and George H. Zenner,
Kenmore, N. Y., assignors to The Linde Air
Products Company, New York, N. Y., a corpora-
tion of Ohio

Application August 19, 1939, Serial No. 290,974

14 Claims. (Cl. 220—15)

This invention relates to constructions for double-walled containers for liquefied gases, and particularly to constructions for double-walled containers having an intervening space that may be evacuated for insulating purposes, whereby the containers are adapted for storing and/or transporting liquefied gases which have relatively low boiling points at atmospheric pressure, such as liquid air and liquid oxygen.

The invention has for its object generally the provision of an improved construction for supporting the inner vessels in a manner which avoids the concentration of stresses in the wall of the outer vessel and employs an arrangement of structural elements for supporting separately inner and outer vessels, especially cylindrical inner and outer vessels.

Another object is to provide improved safety connections for double-walled containers with evacuated insulating spaces whereby damage from pressure developing in the evacuated space is positively avoided and such pressure as may develop released quickly to the atmosphere.

Still another object is to provide a construction which avoids the imposition of loads and resulting deflections on the wall of the outer vessel due to the load in the inner vessel.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawing, in which:

Fig. 1 is a view, partly in elevation and partly in vertical section, showing a double-walled cylindrical container for a liquefied gas, such as liquid oxygen, constructed in accordance with the invention and adapted to have the insulating space evacuated;

Fig. 2 is a similar view on a reduced scale showing a modified form of the invention;

Fig. 3 is an enlarged fragmentary sectional view showing a detail in construction of Fig. 2; and

Fig. 4 is an enlarged vertical sectional view showing the construction of a safety relief device that may be employed when an evacuated insulating space is employed in the invention.

Referring now to the drawing, and in particular to Fig. 1, 10 denotes generally an exterior frame composed of uprights, or leg members, and connecting or cross members 10x, from which a wall 11 of an inner vessel of the container is suspended, such vessel being adapted to hold a liquefied gas that is to be placed or stored in the container either with or without the aid of a lining or basket (not shown). Outside of the vessel 11 and disposed in rigid spaced relation with respect thereto is a second or outer vessel 12 which is also supported from the frame 10, the manner of support being described below. The space intervening between the vessels thus provided is a closed space adapted for insulating purposes and preferably has a filling of a powdered insulating material. There being no communication with the outside except that which may be provided through a special connection in the wall of the outer vessel, the intervening space may readily be evacuated when desired.

A valve controlled filling connection 13 is provided leading from a suitable point without the outer vessel through the intervening space to a point within the inner vessel. Similarly, a valve controlled withdrawal connection 14 is provided leading from a point near the bottom of the vessel 11 through the intervening space to a suitable external point and has a suitable coupling means 15 by which it may be connected to a suitable discharge receiving device at a place of use.

In accordance with the present invention, each pipe connection here employed is provided, at the point where it passes through the wall of the vessel 12, with sealing means of a character such that it transmits relatively little heat to the connection. An exemplary illustration of such means is shown in detail on the connection 14, and consists of a conical wall 16 of a material having a relatively poor thermal conductivity and shaped to interpose a relatively long conducting path of relatively small cross-section so that a relatively large amount of thermal resistance to the passage of heat from the vessel 12 to the connection 14 is provided. The cone 16 is welded or otherwise integrally attached both to the wall of vessel 12 and to the connection 14. Such connection is preferably so shaped and disposed that expansion, contraction, and other stresses are accommodated without liability of incurring a break in what is intended to be a hermetically sealed wall. There may be also connected, in association with the connection 14, or otherwise, one or more trycocks, such as shown at 14'. Other standard accessories, such as a

liquid-level gauge, may also be connected to the inner vessel.

The inner vessel 11 is here provided with a conventional blowdown or evaporation connection 17 which is valve controlled and when closed is adapted to afford relief for any excess of pressure that may accumulate, through a safety valve 18 that is connected thereto; there being also preferably attached a bursting diaphragm device 19, of any known construction. By such means quick relief is afforded in the event of any rise in pressure in the vessel 11.

In order that the space between the walls of the vessels 11 and 12 may be evacuated after assembly, or while in service, a valved connection 20 is attached to the outer vessel 12 and arranged to communicate with the space within. The outer end of connection 20 has a coupling 21 adapted for attachment to a suitable vacuum pulling means, indicated diagrammatically in the drawing as a pump. A suitable vacuum pulling means of this character may be, for example, a mechanical vacuum pump. To the connection 20 there is preferably attached a vacuum space relief device 22 which has a diaphragm adapted to be burst should any undesired pressure occur in the space between the walls of the vessels 11 and 12. Any suitable device of this latter character may be employed, for example, that shown in Fig. 4.

In the construction here shown, the inner vessel 11 is supported directly from the frame 10 and not from the inner surface of the walls of vessel 12. To this end, the inner vessel 11 has a suspending means comprising a girth member 23 having a bracket or lug, as shown at 23', at each end, such means being made fast to the outer surface of vessel 11 if desired. Attached to the lugs are suspending rods or cables 24, each of which extends generally upwardly and outwardly and is secured in suitable means, such as a collar 25 made fast to frame 10 at a suitable point, for example, to the cross-member 10x. The rods 24 are preferably also of relatively low thermal conductivity and may be constructed of a material having such property, as well as a high tensile strength, for example, of stainless steel. Each such rod 24 is passed through the collar and is threaded at its upper end for engagement with one or more nuts 26 which are screwed on the end of the rod. The collar is preferably secured to the frame by brazing or welding and has a reduced lower end for the reception of an enveloping sleeve 27 which houses the rod 24; such sleeve includes an expansion joint 30 and is brazed at its lower end onto the wall of vessel 12 and at its upper end to collar 25.

In order that this supporting structure which passes through the wall of vessel 12 and has low thermal conductivity may be also hermetically sealed against the passage of gas into or out of the space between vessels 11 and 12, a housing or cap 28 is disposed over the nuts 26 and brazed or welded onto the collar 25; the joint between collar and cap being shown as made by reducing the top of the collar sufficiently to fit snugly into the cap, the joint being preferably closed by soldering or brazing.

To afford a rigid support for a spherical vessel 11 in the above described manner at least three rods or cables are required. Four or more cables, however, may be employed, especially where the frame 10 is square or rectangular in plan. Still more, for example, six or eight, may be employed when the nested vessels have the

form of elongated vessels with spherical ends, or have the shape of oblate ellipsoids.

To support the outer vessel 12 in place, additional supporting means are provided between the frame 10 and the outer wall of vessel 12, such means being structurally independent of the support for vessel 11. Since sleeves 27 are here extensible, such means is independent thereof and comprises web members 29, interposed as shown, each having one edge bolted or welded to a leg member of frame 10 and an opposite edge in contact with or made fast to the outer wall of vessel 12. The web members, however, may be dispensed with where it is convenient or desirable to braze or weld the outer wall of vessel 12 directly to the leg members.

In order to convert the insulating space between the walls of containers 11 and 12 into one in which the heat transfer occurs substantially entirely by conduction of low value, the space is first filled with a finely divided or comminuted substantially dry insulating material, such as asbestos fiber, magnesium carbonate, or the like, and thereafter evacuated.

When such material has been properly disposed in the space between the walls of vessels 11 and 12, and distributed so as to avoid uneven packing or the formation of pockets, a vacuum of sufficiently low value is pulled by suitable vacuum pulling means attached through the connection 20 until the thermal conductivity of the insulating space is of a desirable low value, for example, the conductivity provided when a vacuum of an order of 0.1 mm. of mercury is pulled; the employment of vacuums of this order for the purpose of increasing the efficiency of powder filled insulating spaces being taught and claimed in copending application, Serial No. 307,945, filed on December 7, 1939, in the name of L. I. Dana.

To permit ready access to the space between the vessels 11 and 12 for the purpose of filling and disposing desired comminuted or powdered insulating material therein, as here proposed, one or more openings are provided in the wall of vessel 12 which preferably have flanges to which a cover may be brazed or welded when it is desired to close or hermetically seal the same. Two such openings are shown for the vessel 12 in the drawing, one at 31 for the top and one at 32 for the bottom.

The vacuum space relief device shown generally at 22 may be of any suitable form but is preferably that disclosed in copending application, Serial No. 307,564, filed December 5, 1939, in the name of H. C. Kornemann and shown in detail in Fig. 4, where it is seen to consist of a chamber 40 which also has an open side surrounded by a flange 41 on which a diaphragm 42 rests, the diaphragm being held in place by means of a retaining member 43 adapted to clamp the edge of the diaphragm and fit over the flange 41. This chamber has openings 44 and 44' through which it is attached or inserted in the conduit 20. Thus the space within the chamber 40 is subject to a vacuum of the same degree that obtains in the space between the walls of vessels 11 and 12. A cutting member 45 is associated with the device in such a manner that it is adapted to cut or pierce the diaphragm 42 in the event that it springs upward by reason of pressure accumulating in the space between the walls of vessels 11 and 12. Any convenient form of cutting or piercing member 45 may be here employed, for example, a cutting

edge of an arm that is attached to the ring 43 over the diaphragm 42.

In operation, the container is filled by connecting the connection 13 to a source of supply of the liquefied gas, such as liquid oxygen, which is to be stored in vessel 11. The flow of the liquefied gas into the container may be controlled by manipulating the valve in connection 13. In order to permit the liquid thus introduced to displace any gaseous filling that may be in the inner vessel, the evaporation connection 17 is opened to the atmosphere, or connected to a gasometer, in the event that it is desired to conserve the gas thus displaced. Liquid may be withdrawn from the container in the usual manner by opening the withdrawal connection 14. In the interim it may be desired to maintain the vessel 11 closed to the atmosphere. This, of course, is accomplished by closing the valve in the evaporation connection 17.

In the modified form of the invention shown in Fig. 2, certain details of which are shown in Fig. 3, the inner and outer cylindrical vessels are shown at 111 and 112 respectively, and are of diameters such that their overall width extends beyond the supporting frame, shown generally at 110. This frame consists of upright leg members tied together at the sides by spaced horizontal channel members 10y that have cross members 10z spanning the ends to unite them rigidly.

The frame structure provided is adapted particularly for the support of cylindrical vessels having spherical ends. Accordingly the outer vessel 112 may be placed in position and supported by web members extending from the leg members at the corners into engagement with the exterior wall of vessel 112. Such members are here shown at 129.

The support of the inner vessel 111 from the frame 110 is provided in a manner similar to that for vessel 11. Sling or side supporting brackets are provided, as shown at 123 in Fig. 3. From such brackets, a rod 124 having low heat conductivity extends upwardly through a collar 125 on the end of sleeve 127 that is welded at its lower end to vessel 112; the rod 124 having nuts 126 in threaded engagement with its upper end and resting on collar 125. Here, the collar is welded or brazed to the sleeve, the latter being secured rigidly by welding or otherwise, in a plate 125' that rests on the channel bars 10y. This structure is protected by providing a covering cap 128 which is soft soldered or otherwise removably secured in place over the nuts 126. Here the expansion joint is shown at 130 and comprises a pair of flanges, sealed at their outer edges and introduced in sleeves 127 at suitable intermediate points.

The container of the present invention when thus equipped has relatively little heat conducted in any manner to the inner vessel and is not only capable of operating at high efficiencies for long periods of time but also meets all the safety requirements for devices of this character and avoids substantially all possibility of damage arising from possible sudden rises in pressure in the outer vessel.

Since certain changes may be made in the above construction and different embodiments of the invention could be made without departing from the scope thereof, it is intended that all matter contained in the above description or shown in the accompanying drawing shall be in-

terpreted as illustrative and not in a limiting sense.

Having described our invention, what we claim as new and desire to secure by Letters Patent is:

- 5 1. In a double-walled container for liquefied gases, the combination comprising an inner vessel for holding a liquefied gas, an outer vessel surrounding and spaced from said inner vessel to provide an intervening insulating space, means including a frame for rigidly supporting said outer vessel, separate means passing through an opening in said outer vessel extending from a yieldable portion of said frame for supporting said inner vessel, and extensible mains in communication with said opening and surrounding and completely enclosing said separate means and connecting said yieldable portion of said frame with said outer vessel and substantially sealing said separate means from the exterior; 15 whereby any deflections in said yieldable portion of said frame are elastically absorbed and the imposition of load stress on the wall of said outer vessel is avoided.
- 20 2. In a double-walled container for liquefied gases, the combination comprising an inner vessel for holding a liquefied gas, an outer vessel surrounding and spaced from said inner vessel to provide an intervening insulating space, exterior supporting means for said outer vessel, anchoring means associated with said external supporting means, extensible hermetically sealed sleeves extending from said outer vessel to said anchoring means, and supporting rods extending from said anchoring means through said sleeves into supporting engagement with said inner vessel.
- 25 3. In a double-walled container for liquefied gases, the combination comprising an inner vessel for holding a liquefied gas, an outer vessel surrounding and spaced from said inner vessel to provide an intervening insulating space, a supporting frame disposed about said outer vessel, anchoring means associated with said supporting frame, hermetically sealed sleeves extending from said outer vessel to said anchoring means, rod means extending from said anchoring means through said sleeves in supporting engagement with said inner vessel, separate means for supporting said outer vessel from said frame, and pipe connections extending through the wall of said outer vessel hermetically sealed within and communicating with said inner vessel.
- 30 4. In a double-walled container for liquefied gases, the combination comprising an inner vessel for holding a liquefied gas, an outer vessel surrounding and spaced from said inner vessel to provide an intervening insulating space, a supporting frame disposed about said outer vessel, anchoring means in said frame, means including rods extending from said inner vessel to said anchoring means for supporting said inner vessels, sleeved sealing means interposed between said anchoring means and said outer vessel, a pipe connection extending through an opening in the wall of said outer vessel and communicating with said inner vessel, and means interposed between said connection and the edge of said wall for hermetically sealing said opening, said latter sealing means being made of a material having relatively low thermal conductivity.
- 35 5. In a double-walled container for liquefied gases, the combination comprising an inner vessel for holding a liquefied gas, an outer vessel surrounding and spaced from said inner vessel to provide an intervening insulating space, a supporting frame disposed about said outer vessel,
- 40
- 45
- 50
- 55
- 60
- 65
- 70
- 75

means extending from said inner vessel to said frame for supporting said inner vessel, means including sleeves surrounding said supporting means extending between said frame and said outer vessel and adapted for hermetically sealing the wall of said outer vessel, and means introducing an expansion joint in each of said surrounding sleeves.

6. In a double-walled container for liquefied gases, the combination comprising an inner vessel for holding a liquefied gas, an outer vessel surrounding and spaced from said inner vessel to provide an intervening insulating space, a supporting frame disposed about said outer vessel, sealing means including sleeves extending from said outer vessel to said frame, rod means extending from said frame through said sleeves in supporting engagement with said inner vessel, other means associated with said frame for supporting said outer vessel, liquid filling and withdrawal connections for said inner vessel in said insulating space, and an expansion element interposed in said sealed sleeves, whereby the support of said outer vessel is sustained entirely by said other means.

7. In a double-walled insulated container for liquefied gases, the combination comprising an inner vessel for holding the liquefied gas, an outer vessel surrounding and enclosing an insulating space about said inner vessel, a supporting frame disposed about said outer vessel, anchoring means on said frame, sleeved means sealed in the wall of said outer vessel and extending to said anchoring means, supporting members extending from said frame to the wall of said outer vessel, supporting connections extending from said inner vessel through said sleeves and made fast in said anchoring means, liquid filling and withdrawal connections for said inner vessel passing to the exterior through said insulating space, an evaporating connection adapted to be closed to the atmosphere, and means for quickly relieving any pressure which may accumulate in said space.

8. In a double-walled insulated container for liquefied gases, the combination comprising an inner vessel for holding the liquefied gas, an outer vessel surrounding and enclosing an insulating space about said inner vessel, a supporting frame disposed about said outer vessel, separate supporting means for said inner vessel including rods attached to said frame and passing through the wall of said outer vessel, sleeved means disposed about said rods and extending between said frame and said outer vessel, liquid filling and withdrawal connections communicating with said inner vessel and disposed in said insulating space, an evaporating connection adapted to be closed to the atmosphere, a bursting diaphragm safety device connected to said evaporating connection, and a second bursting diaphragm safety device connected to said evacuating means.

9. In a double-walled container for liquefied gases, the combination comprising an inner vessel for holding the liquefied gas, an outer vessel surrounding and spaced from said inner vessel thereby providing an intervening space for insulating purposes, a supporting frame externally associated with said outer vessel, sleeved means sealed in the wall of said outer vessel and provided with anchoring means made fast on said frame, supporting webs extending from said frame to the wall of said outer vessel, and supports extending from the wall of said inner vessel and passing through said sleeved means and made fast in said anchoring means; said sleeved means and an-

choring means being constructed in a manner making a gas-tight seal against the impairment of any vacuum in said space.

10. In a double-walled container for liquefied gases, the combination comprising an inner vessel for holding the liquefied gas, an outer vessel surrounding and spaced from said inner vessel thereby providing an intervening space for insulating purposes, a supporting frame having at least a part including a base externally associated with said outer vessel, supporting means in said frame extending into engagement with the wall of said outer vessel, other supporting means extending between said frame and said inner vessel and passing through openings provided in the wall of said outer vessel, and means for hermetically sealing the passage of said other supporting means through said openings.

11. In a double-walled container for liquefied gases, the combination comprising an inner vessel for holding the liquefied gas, an outer vessel surrounding and spaced from said inner vessel thereby providing an intervening space for insulating purposes, a supporting frame having at least a part including a base externally associated with said outer vessel, supporting means in said frame comprising members extending into engagement with the wall of said outer vessel, other supporting means extending between said frame and engaging with the wall of said inner vessel and passing through openings provided in the wall of said outer vessel, and sleeved means disposed about said other supporting means for hermetically sealing said openings.

12. In a double-walled container for liquefied gases, the combination comprising an inner vessel for holding the liquefied gas, an outer vessel surrounding and spaced from said inner vessel thereby providing an intervening space for insulating purposes, a supporting frame having at least a part including a base externally associated with said outer vessel, supporting members in said frame in rigid supporting engagement with the wall of said outer vessel, other supporting members including rods extending between said frame and said inner vessel and passing through openings provided in the wall of said outer vessel into engagement with the wall of said inner vessel, and sleeve-like members about said rods for hermetically sealing said openings to the passage of said other supporting connections.

13. In a double-walled container for liquefied gases, the combination comprising an inner vessel for holding the liquefied gas, an outer vessel surrounding and spaced from said inner vessel thereby providing an intervening space for insulating purposes, a supporting frame having at least a part including a base externally associated with said outer vessel, anchoring means on said frame, sleeve-like members sealed in openings provided in the wall of said outer vessel and extending to said anchoring means, supporting members in said frame engaging the wall of said outer vessel, means including brackets supporting the outer wall of said inner vessel, other supporting members extending from said brackets through said openings and made fast in said anchoring means, and means on said sleeves and anchoring means for making a gas-tight seal therefor against the impairment of any vacuum in said space.

14. In a double-walled container for liquefied gases, the combination comprising an inner vessel for holding the liquefied gas, an outer vessel surrounding and spaced from said inner vessel thereby providing an intervening space for insu-

lating purposes, a supporting frame disposed about said outer vessel, anchoring means on said frame, sleeves sealed in openings provided in the wall of said outer vessel and extending to said anchoring means, supporting members extending from said frame into engagement with the wall of said outer vessel, other supporting mem-

bers including rods extending from said inner vessel through said openings and made fast in said anchoring means, and means for hermetically sealing the upper ends of said sleeves.
